BRASSIÈRE

Bertha Greenbaum, Cleveland, Ohio

Application May 31, 1934, Serial No. 728,293

5 Claims. (Cl. 2—42)

This invention relates to a brassière and the main object of the invention is to provide a new and improved garment of this type which will effectively mould and support the breasts.

5 Another object of the invention is to provide a brassière which will comfortably support and mould large and pendulous breasts and preserve the artistic and youthful contour of the breast line.

10 Another object of the invention is to provide a brassière which is constructed to maintain the breasts in separate units and in their natural position and also preserve the dividing line between the breasts.

15 Another object of the invention is to provide a brassière that will hold and support the breasts in their natural position without placing undue strain on the shoulder straps.

20 Further and more limited objects of the invention will appear as the description proceeds and by reference to the accompanying drawing in which Fig. 1 is a view in front elevation of my improved brassière; Fig. 2 is a detail sectional view showing the brassière in position on the body and Fig. 3 is a fragmentary view in front elevation showing a slightly modified form of brassière.

25 Referring now to the drawing, the reference character 1 designates a strip or body encircling band, which is preferably formed partly or entirely of elastic material and which has a straight upper edge and is of the same width throughout its length. The reference characters 2 and 3 designate a pair of breast receiving cups or pockets which are attached to the exterior of the band 1 about their lower edges. The lower edges of the cups are gathered or tucked so that a stretching of the band 1 will not distort the cups. These cups are preferably, though not necessarily, formed in two pieces. The cups extend some distance above the upper edge of the band and extending about the upper edges thereof is an elastic band 4 which is preferably enclosed within a hem or fold thereof. The two cups are secured together by a centrally disposed laterally extending seam 5. The seam 5 is also secured to the band 1 and divides the cups into a pair of breast receiving pockets. The natural dividing line between the breasts is therefore maintained throughout all movements of the body incidental to exercise or sports.

30 One of the important features of my brassière resides in the body encircling band which has a straight upper edge and is of substantially the same width throughout its length. The stretch-

ing of the band does not disturb the dividing line between the breasts and does not distort the cups or place too great a pressure on the breasts. When the garment is worn, the band 1 is slightly stretched and the major portion of the breasts assumes about the position shown in Fig. 2. The cups and the band cooperate to mould and support the breasts in their natural position and preserve the youthful and artistic contour of the bust without placing any excessive pressure on the breasts even though the breasts be large or pendulous. The cups are preferably attached to the band adjacent the lower edge thereof in the larger sizes; but may be changed, depending upon the size and type 15 of woman for which the garment is designed.

35 The reference characters 6 and 7 designate the usual shoulder straps which hold the upper portions of the cups in place. Due to the shape and construction of the garment the breasts are 20 pressed or moulded to their natural shape and contour and the weight of the breast is not carried by the shoulder straps. The dividing line between the breasts is preserved regardless of how tight the band may be stretched as the seam 25 5 is not displaced. Any stretching of the band 1 is equally distributed around the bust because the upper edge of the band is straight and the band is of the same width or depth throughout its length. If desired, only that portion of the 30 band opposite the cups may be made elastic. The garment is preferably fastened by suitable hooks 8 and eyes 9 and should be of such length as to be placed under a slight tension when fastened.

40 In Fig. 3 I have disclosed a slightly modified form of garment in which the band 1 is of less width or depth relative to the size of the cups. In this form the cups are not secured to the band about their lowermost edges. In other respects this garment is identical with that shown 45 in Figs. 1 and 2. This brassière is designed for the younger and more slender woman.

45 It will now be clear that I have provided a brassière which will accomplish the objects of the invention as hereinbefore stated. The embodiments of the invention disclosed are to be considered merely as illustrative and not in a limiting sense as various changes may be made in the shape and size of the various parts of the garment without departing from the spirit of the invention, the dominating features of which have been set forth hereinbefore.

50 Having thus described my invention, what I claim is:

55

1. A brassière comprising a body encircling band of elastic material of substantially the same width throughout its length and having a straight upper edge and a pair of breast receiving cups attached to the exterior of said band, said cups being attached to said band adjacent the lower edge thereof and the major portion of said cups being disposed below the upper edge of said band.
2. A brassière comprising a body encircling band of elastic material of substantially the same width across the front portion thereof and having a straight upper edge and a pair of breast receiving cups having the lower edges thereof attached to the exterior of said band, the upper edge of said band being disposed considerably above the lower edges of said cups.
3. A brassière comprising a body encircling band the front portion of which is formed of elastic material having a straight upper edge, a pair of breast receiving cups secured to the exterior of said front portion and having a portion thereof disposed considerably below said straight edge and exterior thereof, and means securing said

cups to said band along the entire lower edge thereof.

4. A brassière comprising a body encircling band the front portion of which is formed at least in part of elastic material and having a straight upper edge, a pair of breast receiving cups secured to the exterior of said front portion and having a portion thereof disposed considerably below said straight edge and exterior thereof, the lower edge of said cups being tucked or gathered to permit stretching of said band without displacing said cups.

5. A brassière comprising a body encircling band the front portion of which is formed at least in part of elastic material and having an upper edge which is maintained substantially straight when the garment is worn on the body, a pair of breast receiving cups attached to the exterior of said front portion and central thereof, and means securing the ends of said cups to the exterior of said front portion, a considerable portion of said cups being disposed below the upper edge of said front portion.

BERTHA GREENBAUM.
